UNITED STATES PATENT OFFICE.

DAVID GRANT, OF CHICAGO, ILLINOIS.

ARCH SUPPORT.

Application filed January 18, 1923. Serial No. 613,479.

To all whom it may concern:

Be it known that I, DAVID GRANT, a citizen of the United States, residing at Chicago, in the county of Cook and State of Illinois, have invented new and useful Improvements in Arch Supports, of which the following is a specification.

This invention relates to an arch support and has for its primary object the construction and arrangement of parts whereby the bones of the foot will be properly acted upon to rectify any displacement or distortion of the bones of the foot.

An object of the invention is the use of an auxiliary support that may be quickly arranged in place for co-action against the metatarsus bones independently of the main arch-supporting elements.

Another object of the invention is the combination of two supports, a main and auxiliary, which may be used together or independently.

Besides the above my invention is distinguished in the manner of shaping the auxiliary support and connecting the same to the main support.

With these and other objects in view the invention will be better understood from the following detailed description taken in connection with the accompanying drawing wherein:

Fig. 1 is a top plan view of the support with part of the cover broken away.

Fig. 2 is a bottom plan view.

Fig. 3 is a longitudinal sectional view on the line 3—3 of Fig. 1.

Fig. 4 is a top plan view of the auxiliary support.

Fig. 5 is a longitudinal sectional view of the auxiliary support.

Fig. 6 is a top plan view of a modified form of the invention.

Fig. 7 is a detail section on the line 7—7 of Fig. 6.

Fig. 8 is a plan view of the auxiliary support.

Again referring to the drawing the numeral 1 designates in its entirety an arch support as constructed in one of my co-pending applications known in this application as the main support, consisting of a base plate 2 and arch supporting plates 3 and 4 which are bowed and detachably engage clips 5 connected to the base. These elements are identical in construction as de-

scribed in my co-pending application, Serial No. 502,939, filed September 24, 1921, with the exception that the clip 5 is provided with a recess 6.

My improved auxiliary support 7, which is shaped and arranged to exert pressure against the metatarsus bones of the foot and more particularly at the point of connection with the phalanges bones of the foot is of convex formation to increase the effective action thereof. In this particular case the auxiliary support is stamped from sheet metal to have a tongue 8 that is passed around the forward edge portion of the base plate with the extreme end positioned in the recess 6. It will be noted that the forward end portion of the auxiliary support rests upon the spring plates 3 and 4 and as a result a certain degree of resiliency is given to the auxiliary support and this action is increased by the novel manner of forming the tongue 8 and connecting same to the base plate.

In Figs. 6, 7 and 8 of the drawings a modified form of the auxiliary support is shown in which the main convex body 20 of the auxiliary support 21 is surrounded by a substantially flat flange 22. Laterally projecting abrupt shoulders 23 are formed on the flange 22 at diametrically opposed points and they are adapted to engage against rivets 24 of the arch support structure for maintaining the auxiliary support in proper position, the shoulders 23 replacing or serving a similar function to the tongue which is formed on the auxiliary support 7.

From the foregoing description taken in connection with the accompanying drawing it will be apparent that I provide a support of two main elements that may act independently or jointly to properly restore the bones of the foot to normal position.

It will also be noted that the auxiliary support may be removed at will and different sized auxiliary supports substituted. It will also be noted the connection is such that slight adjustment may be accomplished. Thus it will be seen that I provide a support that may be readily shaped and adjusted to various shaped feet so as to properly correct the same.

It is, of course, to be understood that the various parts may be shaped in other manners and the auxiliary support constructed of other materials than sheet metal and may

be shaped in various other manners and, therefore, I do not desire to be limited in any manner except as set forth in the claims hereunto appended.

5 Having thus described my invention what I claim is:

1. An arch support comprising a base plate, arch supporting plates yieldably connected to the base plate, and means for en-
10 gaging the metatarsus bones of the foot and detachably connected to the base plate.

2. An arch support comprising a base plate, arch supporting plates yieldably connected to the base plate, and means or en-
15 gaging the metatarsus bones of the foot and detachably connected to the base plate and further having yieldable movement assisting

the yieldable action of said arch supporting plates.

3. An arch support comprising a base 20 plate, yieldable arch supporting plates connected thereto, and an auxiliary support having one end portion yieldably engaging said plates, and its other end portion yieldably engaging the base plate.

4. In combination with an arch support including a base plate and yieldable arch supporting plates, an auxiliary support having a tongue detachably engaging the base plate, said support yieldably engaging the 30 said arch supporting plates.

In testimony whereof I affix my signature.

DAVID GRANT.
